UNITED STATES PATENT OFFICE.

JAKOB E. NOEGGERATH, OF SCHENECTADY, NEW YORK, ASSIGNOR TO GENERAL ELECTRIC COMPANY, A CORPORATION OF NEW YORK.

INSULATOR FOR HIGH-TENSION TRANSMISSION SYSTEMS.

974,177.

Specification of Letters Patent.

Patented Nov. 1, 1910.

Application filed February 9, 1910. Serial No. 542,862.

To all whom it may concern:

Be it known that I, JAKOB E. NOEGGERATH, a citizen of the United States, residing at Schenectady, county of Schenectady, State of New York, have invented certain new and useful Improvements in Insulators for High-Tension Transmission Systems, of which the following is a specification.

The present invention relates to electrical 10 insulators and more especially to insulating units for high tension power circuits.

In the transmission of electrical power over considerable distances, economy of construction necessitates that the current be at 15 high tension, often above one hundred thousand volts, and that the number of supporting towers for the conductor wires per mile be few. As a result of these practical requirements, the insulators for the conductor 20 wires have imposed upon them the double function of withstanding the high potential current and the great mechanical strains due to the weight and tension of the long spans of wire. It has been the practice during 25 recent years to employ chains of insulating units of moderate size rather than single large insulators on high potential circuits so as to subdivide the potential differences imposed upon the respective units, but the mechanical stresses on a unit are in no way reduced by connecting it in series with other 30 insulators.

The object of my invention is to provide an insulating unit which, in addition to possessing high electrical properties, will withstand excessive mechanical stresses without affecting or impairing the electrical properties and which may be manufactured at moderate cost.

40 My invention may be embodied in various ways, some of which are indicated in the accompanying drawing forming a part of this specification, in which—

Figure 1 is a vertical axial section of an 45 insulating unit in which the anchoring balls for the bolt are inserted through a channel formed in the insulating member; Fig. 2 is a horizontal section on line 2—2 of Fig. 1, showing method of anchoring insulating 50 member to the bell; Figs. 3 and 4 are vertical axial sections of an insulating unit in which the anchoring balls for the bolt are inserted prior to the introduction of the bolt head; Fig. 5 is a vertical axial section of an 55 insulating unit in which the anchoring balls

for the bolt are inserted through a channel formed at the axis of the bolt and the bell anchored to the insulating member by balls; Fig. 6 is a vertical axial section of an insulating unit with two insulating members 60 and all parts anchored similar to the construction shown in Figs. 1 and 2; and Figs. 7 and 8 show modified forms of balls drawn to enlarged scale.

In all of the constructions shown in the 65 drawings, the insulating unit comprises an upper strain member in the form of a supporting bell 1, one or more insulating members 2 and a lower strain member in the form of a bolt 3.

The bell 1 is preferably of cast iron and provided with an internal groove 4 near its lower end, and at its upper end with a holding projection 5 in which is formed a recess 6 for receiving the end of a strain bolt 75 3 of an upper insulating unit (not shown).

The insulating member 2 is preferably of porcelain with its main portion 7 made in the form of a flaring disk, and its upper central section 8 in the form of a cylindrical 80 knob with a peripheral groove 9 near its base and a central cavity 10 enlarged at its inner end to form a circular inclined shoulder or ledge 11 at a distance from the mouth of the cavity.

The strain bolt 3 is of round machine 85 steel or wrought iron with a circular head 12 at each end and a ball retaining flange 13 some distance below the upper head. It is anchored in the central cavity 10 of the 90 insulating member by metal slugs or balls 14, which, when forced into intimate contact with the insulating material, will compress somewhat and distribute the pressure instead of operating to crush the insulation. 95 The slugs or balls may be entirely of brass or copper, or as shown in Fig. 7 of a hard metal 14 coated with a more yieldable metal, or as shown in Fig. 8 of a hard metal provided with protuberances which afford a 100 number of points of contact.

In the construction shown in Figs. 1 and 2, the insulating member has a channel 15 formed in the wall of the lower or contracted portion of the cavity 10, and the bolt 105 flange 13 is cut away at 16 so that after the end of the bolt has been inserted in the cavity the anchoring balls 14 may be passed through the channel to the space between the inner side of the bolt head 12 and the 110

ledge 11 of the insulator where they are automatically distributed by the crowding in of the necessary number. By giving the bolt a partial turn the cutout section of the bolt 5 flange 13 is carried out of register with the insulator channel 15 and serves to lock the balls in place. The insulating member 2 is anchored to the bell 1 by means of a wire 17, which may be cut in sections, inserted 10 through a tangential hole 18 cut in the rim of the bell and forced around in the space formed by the complementary grooves 4 and 9.

In the construction shown in Figs. 3 and 15 4, the center bolt 3 has a depressed upper end and a diagonal slot 19 cut in its head extending from the depression to the space between the under surface of the head and the retaining flange 13. In assembling the 20 parts the required number of balls 14 are introduced into the cavity 10 before the insertion of the bolt head, and then by slight manipulation of the bolt they are caused to pass through the slot 19 to space between 25 the lower surface of the bolt head and the ledge 11 on the insulating member.

In the construction shown in Fig. 5, the bolt 3 is provided with a central bore 20 extending from the lower end to near the upper end where it turns and emerges just below the head. The anchoring balls 14 are passed through the bore 20 and distribute themselves between the ledge 11 and bolt head 12 as in each of the preceding cases. 30 The insulating member 2 is anchored in the bell 1 by a number of balls 17 introduced into the space formed by the complementary grooves 4 and 9 through a hole 18' in the lower end of the bell.

40 In the construction shown in Fig. 6, there are two insulating members 2 and 2' with the knob portion 8' of the latter anchored within the cavity 10 of the former by slugs or balls 14 introduced through complementary channels 15' formed in both members 2 similar to that shown in Fig. 2. The insulating member 2 is anchored in the bell 1 and the bolt 3 is anchored in the insulating member 2' in the same manner as in the 45 form of device shown in Figs. 1 and 2.

In order to retain the parts in fixed relation and to exclude moisture, I fill the unoccupied spaces between the several parts of the insulating unit with suitable cement or 50 other self hardening substance 21. It is, however, to be noted that the yieldable metal anchoring means resist the tendency of the parts to separate when subjected to tensile strains and that the cement is substantially 55 passive in this respect.

I do not desire to restrict myself to the particular form or arrangement of parts herein shown and described, since it is apparent that they may be changed and modified without departing from my invention. 65

What I claim as new and desire to secure by Letters Patent of the United States, is,—

1. The combination with an insulator, of a strain member sustained by said insulator, and yieldable slugs for distributing the pressure imposed upon the insulator by said strain member. 70

2. The combination with an insulator having an internal shoulder, of a strain bolt having a head disposed in proximity to said shoulder, and anchor slugs disposed between 75 said shoulder and the head of said bolt.

3. The combination with an insulator having a shouldered cavity, a strain bolt having a head disposed within said cavity, and anchor slugs disposed between the outer side 80 of said bolt head and the shoulder of said cavity.

4. The combination with an insulator having a cavity enlarged at its inner end to form an internal shoulder and provided with a groove in the wall of the outer portion of the cavity, of a strain bolt having a head disposed in the enlarged portion of said cavity, and anchor slugs insertible 90 through said groove into the space between the outer surface of said bolt head and the shoulder of said cavity.

5. The combination with an insulator having a peripheral shoulder, of a supporting bell surrounding the grooved portion of the insulator and provided with an internal complementary shoulder, and an anchor wire disposed in the space between said shoulders. 95

6. The combination with an insulator having a circular portion provided with a peripheral groove, of a supporting bell surrounding said circular portion of the insulator and provided with a groove opposite the insulator groove and with an aperture 100 tangential to said groove.

7. The combination with an insulator having an internal shoulder, of a strain bolt having a head disposed in proximity to said shoulder, anchor slugs between said shoulder and bolt head, a supporting bell surrounding the shouldered portion of the insulator, and cement filling the unoccupied spaces between said parts. 110

In witness whereof, I have hereunto set my hand this 7th day of February, 1910.

JAKOB E. NOEGGERATH.
